By *John Neudell* Atty.

UNITED STATES PATENT OFFICE.

WILLIAM ABIGT, OF EVANSVILLE, INDIANA.

HOT-AIR FURNACE.

Application filed December 27, 1921. Serial No. 525,108.

To all whom it may concern:

Be it known that I, WILLIAM ABIGT, a citizen of the United States, residing at Evansville, in the county of Vanderburgh and 5 State of Indiana, have invented certain new and useful Improvements in Hot-Air Furnaces, of which the following is a specification.

This invention relates to hot air furnaces 10 of the class embodying an upper drum or "radiator" fed by a plurality of inlets from the combustion chamber.

My improvements insure a uniform draft 15 on the fire, eliminate tendency of the draft to draw only at the back of the radiator, and effect better heating of the radiator so that a more nearly maximum radiation is obtained therefrom, and the prevention of down or back draft and puffing of smoke 20 and gases out through the door of the fire bowl when the door is opened or while fresh fuel is being thrown into the fire bowl.

A practical embodiment of my invention 25 such as has been found to be of commercial utility, is hereinafter described and disclosed in the accompanying drawings but I wish it understood that the principles involved may be carried out in other embodiments than that specifically described and 30 illustrated. The disclosure, therefore, is not to be considered in limitation of the scope of the invention.

In the accompanying drawings:—

Figure 1 is a side elevation partly in section.

Fig. 2 is a front elevation partly in section.

Fig. 3 is a plan view of the radiator.

Fig. 4 is a bottom view thereof.

Fig. 5 is a plan view of the lower section 40 of the combustion chamber, dotted lines representing the air feeding means; and

Fig. 6 is an enlarged plan view of the 45 duplex air inlet, a part of the air feeding ring being shown in section.

My improvements are shown in connection 50 with a substantially complete hot air furnace for the purpose of disclosing their relationship thereto, but it is to be understood that those parts of the furnace which are not directly related to the improvements need not necessarily be used.

The ash pit section appears at 1; the fire bowl or pot is shown at 2.

Surmounting the fire bowl or pot is the 55 lower section 3 of the combustion chamber, to the lower part of which section my improved air feeding devices are attached. The upper section 4 of the combustion chamber is suitably connected to the lower section 3 thereof, section 4 having its edge fitting into a channel 3^a in section 3.

The upper section 4 supports the radiator or heat drum, the latter being composed of a lower section 5 and an upper section 6, section 5 having channels 5^a to receive the edges of the section 6. The parts 7 are for connection to the flue leading to the chimney.

The sections 5 and 6 comprise a hollow annular radiator into which the heat, gases, and other products of combustion pass en route to the smoke flue, thereby causing the radiator to radiate the heat for heating purposes.

A defect common to the radiators of hot air furnaces as heretofore constructed has been that the draft from the combustion chamber has tended to go directly to the rear of the radiator so that the radiator 80 has not been adequately heated, this being due to the location of the outlets or to take-offs through which the heat passes from the combustion chamber to the radiator. Furthermore, the take-off commonly used in this 85 general type of hot air furnace has failed to prevent gases and smoke from puffing out through the door to the combustion chamber, particularly when fresh fuel has been introduced onto the fire.

While it has been proposed heretofore to connect the radiator with the combustion chamber by a plurality of take-offs, ducts, nipples, or pipes, I am not aware that earlier constructions have provided for equal distribution of the heat, gases, and other products of combustion in the radiator nor for preventing the down draft which results in the "puffing" heretofore explained. I have, therefore, provided an improved nipple, 100 duct, or take-off arrangement whose object is to substantially equally distribute the draft into the radiator so that a maximum heating effect will be obtained; and, further, down draft, with resulting "puffing" will be 105 obviated.

With the foregoing object in view there is provided the take-offs, nipples, or pipes 8

and 9 projecting downwardly from the lower section 5 of the radiator on opposite sides thereof, and the nipple, duct, or take-off 10 projecting downwardly from the section 5 at the front thereof, said nipples or take-offs being tightly received in openings 11, 12, 13, respectively, provided in the top of the upper section 4 of the combustion chamber. To further insure as nearly equal distribution as possible, the lower and upper sections 5 and 6 of the radiator are provided with inwardly projecting hollow parts or sections 14 and 15, respectively, which are braced at 16. The section 14 is provided with a downwardly extending nipple or take-off 16 which is disposed substantially at the center of the radiator and fits tightly in an opening 17 in the upper section 4 of the combustion chamber. A support or lug 18 which is cast integral with the section 5, rests upon the top of the section 4 to assist in supporting the radiator.

It will be observed that no direct connection is provided between the extreme rear part of the radiator and the combustion chamber and hence the draft is compelled to pass completely around or through the radiator before escaping at the outlet 7. Furthermore, by providing the additional parts 14, 15, 16, the draft above the center of the fire is taken off in such manner that it is compelled to heat this additional part of the radiator before splitting to pass in opposite directions around and through the radiator. The four outlets for the draft which are provided by the take-offs or nipples 8, 9, 10 and 16 and the absence of a take-off for the rear of the radiator, insures an even distribution of the heat, gases, and products of combustion in the radiator and the imparting to the latter of a relatively large percentage of the heat units carried thereby. Additional to this, the draft taken off in this manner, insures a regular and even consumption of the fuel so that the efficiency of the latter is increased. The provision of the take-off 10 at the front of the radiator insures the creation of a draft vertically in front of the door to the fire bowl and combustion chamber, which draft is supplemented by reason of the other take-offs, and this draft through the take-off 10 prevents "puffing" hereinbefore described.

Secured to the under side of the forwardly projecting part 3^b of the lower section of the combustion chamber is a duplex air inlet 19 which is a casting provided with suitable ears 20 by which it is bolted as at 21 to said part 3^b. A suitable door 22 is used to cover the mouth of the duct 19 so that any desired control of the air may be had.

The section 3 is provided with an arc-shaped seat 23.

The ends 24 of the duplex air inlet 19 pass through openings in the section 3 and pro-

ject beneath the seat 23 as shown at 24^a, said projecting parts being offset.

A hollow air feeding or blast ring 26 is provided which has a flange 27 constructed and shaped to fit the seat 23, said ring having openings 28 in its side which receive the projecting ends 24 of the duplex air inlet 19 whereby air entering through said inlet has access to the interior of the hollow ring 26.

The ring 26 is of a dimension and shape adapting it to fit into the tapered lower end of the section 3 which supports it, the rotation of said ring being prevented by the flange 27 and seat 23, said parts also assisting in the support of the ring. The ring is provided with air discharge slots 29 which are preferably placed spaced at regular intervals on the interior thereof except that the continuity of these slots is broken adjacent the ends of the flange 27. Supplemental slots 30 are, however, provided at that portion of the ring between the openings 28. The slots 29 are located on the under, or rounded face of the ring so that they will discharge the air in numerous jets or sprays down onto the fuel in the fire bowl but will be so disposed that they cannot receive fuel thrown into the fire bowl. In brief, these slots are arranged so that they cannot become clogged.

The air, in any desired quantity, may be drawn into the blast ring 26, according to the extent to which the door 22 is open. The chimney draft on the heater is all that is necessary to draw in an adequate supply of air (when door 22 is open) for delivery uniformly over the fire when it reaches the slots 29. As the air inlet 19, but more particularly the ring 26, is heated, the air is pre-heated before it is discharged onto the fire. Combustion may thus be increased, particularly when fresh fuel is introduced. The manner in which the ring 26 is supported, enables it to be removed without difficulty whenever desired.

I claim:

1. In a hot air furnace, the combination with the combustion chamber, of an endless radiator located thereabove, and take-offs or outlets connecting the sides and front of the radiator with the sides and front of the combustion chamber, the rear part of the radiator having no take-off connection with the combustion chamber.

2. In a hot air furnace, the combination with the combustion chamber, of an endless radiator having a hollow part projecting inwardly thereof from the front of the radiator, a take-off or outlet connecting the front of the radiator with the front of the combustion chamber, other outlets connecting the sides of the radiator with the sides of the combustion chamber, and an outlet connecting the combustion chamber with the in-

wardly projecting part, the rear part of the radiator having no take-off connection with the combustion chamber.

3. In a hot air furnace, the combination 5 with the combustion chamber, of an annular radiator having a hollow part projecting radially thereof from the front of the radiator to the center thereof, a take-off or outlet connecting the front of the radiator with

the front of the combustion chamber, other 10 outlets connecting the sides of the radiator with the sides of the combustion chamber, and an outlet connecting the radially projecting part with the combustion chamber, the rear part of the radiator having no take- 15 off connection with the combustion chamber.

In testimony whereof I affix my signature.

WILLIAM ABIGT.
